CHAIR

Robert E. Kjer Jakobsen, Manhattan Beach, Calif., assignor to Virtue Bros. Mfg. Co., Los Angeles, Calif., a corporation of California

Application March 26, 1956, Serial No. 40,770

Term of patent 14 years

(Cl. D15—1)

Fig. 1 is a side elevational view of a chair, showing my new design.

Fig. 2 is a front elevational view of the major portion of the chair back illustrating the center decorative element and with the lower ends of the side rods broken away for convenience of illustration.

The dominant features of the design reside in the portions shown in the drawing in full lines.

I claim:

The ornamental design for a chair, substantially as shown and described.
